WIRELESS-TELEGRAPH DETECTOR.

1,145,658.

Specification of Letters Patent.

Patented July 6, 1915.

Application filed April 27, 1907. Serial No. 370,651.

To all whom it may concern:

Be it known that we, WILLIAM E. ASHTON and AUSTEN M. CURTIS, citizens of the United States of America, and residents of the borough of Brooklyn of the city of New York, county and State of New York, have invented a certain new and useful Wireless-Telegraph Detector, of which the following is a specification, the same being a full, clear, 10 and exact description of the invention, such as will enable others skilled in the art to which it appertains to make and use the same.

This invention relates to wireless or radio 15 telegraphy, and in particular to receivers of that class of current or wave responsive devices in which the susceptibility of the impulses, waves or variations of the current is inherent in the device, which is also self- 20 acting or self-restorative, and therefore always in condition to be influenced by the currents or waves, and which may be adjusted to different degrees of pressure, as well as to an improved arrangement of the 25 wave responsive device in connection with the ordinary apparatus of the receiving station, and it has for its object the provision of a wave responsive or detecting device of the character specified, and of certain novel 30 features of construction and arrangement of parts, all of which will be hereinafter described and illustrated in the drawings.

In order to enable our invention to be 35 fully understood, we shall proceed to explain the same by reference to the drawings which accompany and form a part of this specification, wherein we have indicated some ways in which we have utilized the invention, and in which—

Figure 1 represents an elevation, partly 40 in section, of one arrangement of the wave responsive device; Figs. 2, 3, 4 and 5 are views showing other specific embodiments and arrangements of the impulse detecting material; Figs. 6 and 7 are views showing 45 in detail, respectively, the holder for the crystalline body, and the divided or bi-faced plate; and Fig. 8 is a diagram of a wave receiving apparatus of simple form.

Like letters of reference indicate like parts in all the views.

Our improved wave responsive or detecting device, broadly stated, comprises a concrete mass or body of a metal compound, 50 and the particular metal compound we pre-

fer to use as the detector of our invention consists of a mass or body of zinc compound as described herein and set forth in the claims, such as consist of zinc, oxygen and manganese in chemical combination such as 60 is commonly or generically designated by us as a species of the red oxid of zinc (1) sometimes found in the form of zinc, oxygen and manganese with a trace of iron (2) or of 65 oxid of zinc and oxid of manganese, and (3) in some forms is designated as zinkite, the latter being a massive or granular body of oxid of zinc and formed, as well as other zinc compounds, sometimes in crystalline conformation. The zinc compound 70 may be of any desired shape and size and is of a comparatively hard and refractory nature and is a comparatively poor conductor of electricity. Zinkite is now known, as was the case with minerals generally, to 75 have been formed by the action of pressure or by having been consolidated under a lower temperature within the earth's crust at a remote period. It has been established that minerals now known as solids, once 80 existed in the liquid or gaseous state, their present structure having been determined in the process of solidification. We prefer to use an oxid of zinc as set forth, such as known as zinkite, solidified as in the manner described, in contradistinction to mere surface oxidation, in such a form as to be of varying thickness in different directions and of sufficient thickness or depth to have 85 at least one thicker projecting portion extending therefrom. This wave responsive material may be utilized in connection with various types of signal receiving apparatus, and may consist, in use, of chemical compounds or crystals having different forms 90 of contact faces as will be seen from an inspection of the drawings.

For example, in Fig. 1, the wave responsive device A is shown as a mass of crystalline material supported in a cup-shaped holder B, having, as illustrated in Fig. 6, a cover B' mounted on an adjusting screw b, which is sustained by a cross-bar D working on rods C and held in position between the opposing springs d and d'; by means 100 of which a variable pressure contact is established at the operative thermojunction between the plate E and the crystalline body A. The eccentrically located divided or bi-faced switch plate E, projecting laterally 105

from its axis and comprising a conducting portion e , as shown in Fig. 7, preferably consisting of platinum, and an insulated part e' , is ordinarily provided with means for adjusting the contact or operative junction between the plate E and the wave responsive device A in a plane at an angle to the axes of the same or in lines not coincident with both of the said axes, and the 10 said plate E is preferably constructed and arranged to be turned around while it is ordinarily adjustably held in contact with the crystalline body by any suitable means, as the screw e^2 . By turning the plate or 15 disk E in the proper direction, to the right or left hand, the wave detecting material may be either included in the circuit, or else cut out of the same at will while traveling in parallel planes.

20 In Fig. 2, the wave responsive device is mounted on a pivoted bar F, and is held against the eccentrically located plate E by means of the spring d^2 . In Fig. 3, the impulse detecting material A' is supported by 25 a flat faced holding device attached to a gravity, and preferably spring, rod G pivoted at g, the strain or tension or pressure of the contact between the body A' and the pointed plate E^2 being adjusted by the 30 weight g'. The part E^2 at the end of the bar G' is eccentric to the axis of the body A'.

In Fig. 4, the wave responsive device A is 35 mounted on a stationary support F, and the eccentrically located plate E which projects laterally from its axis and comprises an electrically conducting element is attached to a rod H' sliding in a support H^2 , and is held in contact with the crystalline mass A by the spring d^3 . It will be noted that in 40 Figs. 1 and 2, the pressure at the operative thermojunction may be adjusted to a fine degree, and that in Fig. 3, the said pressure may still be adjusted, although to not so great an extent, while in Fig. 4, the full and 45 uncontrolled positive pressure of the spring is exerted, thus insuring a good pressure or mechanically firm and electrically conducting contact.

In Fig. 5 is shown a concrete mass of the 50 material forming the wave detecting device A ^{2} , to which the ends of the wires or conductors may be secured in any suitable manner, as by being turned or twisted around the same.

In Fig. 8, the wave responsive material A 55 serves to support a body consisting of a platinum plate E^3 , the contact between the parts being regulated by means of the screws e^3 . In the latter figure an arrangement of a receiving station is shown, and it will be observed that in the circuit illustrated, no battery or local source of electromotive force is used, as with the employment of the wave responsive herein shown and described, no 60 battery whatever is necessary in receiving

the signals or impulses of the electric waves. The said receiving station comprises an aerial wire J, a ground connection J, and a signal device in electrical connection with the ground connection consisting preferably 70 of the ordinary magneto telephone receiver K.

The construction of the rotary and longitudinally adjustable cup or cylindrical shaped holder B, forming a circuit conductor, and the therein contained mineral or conducting material A, A', shown in the various figures, is disclosed particularly in Figs. 3 and 6, in which the said impulse detecting materials A, A', are formed with a flat rear face 80 in large aread fixed mechanical contact (relative to the minute or small aread adjustable mechanical contact between the mineral or conducting materials A, A' and the non-aligned conductors E, E ^{2}) with the 85 rear and also with the side portions of the cup-shaped holder B, and supported in the aforesaid figures by the rods F, B G, the separate parts being held together in operative contact by springs in Figs. 2 and 4, or 90 by adjustable means, as by gravity, in Fig. 3; one at least of the circuit conductors, as the conducting body E, being preferably formed of different material than the mineral or solid conducting material, which latter is of high resistivity and cooperatively 95 with the other conducting body possesses thermo-electromotive power, or the property of transforming or converting the energy received over the antennæ into a different form.

It will be noted that the freely longitudinally movable and rotatable device H' supporting the circuit conductor E is eccentrically located as regards the axis of the eas- 105 ing B of the solid electrically conducting material, so that its axis of rotation will not coincide with the axis of the conducting material, and that the spring d^3 holds the other conductor E in operative connection with 110 the solid electrical conducting material A with a good, positive, pressure or substantially perfect contact, the point of which contact is preferably laterally adjustable. In this application a solid electrically conducting material is shown as preferably 115 having a single operative contact point, which may (in connection with a conducting body) operate by the variation of resistance due to the heating of a small part of the 120 mass, thereby obtaining the necessary heat producing resistance, the amount of heat thus generated being so much at the said point that there may exist a sufficient pre-ponderance of thermo-electromotive force of 125 one sign to operate the telephone receiver, the oscillating current therefore being trans- formed, or converted, or rectified into a di- rect current.

As no outside source of electricity is nec- 130

essarily used in connection with our wave responsive device, no noise or frying sound is heard, as is the case with other receivers when batteries are used in their circuit. 5 Consequently, our detector is much more sensitive than those heretofore used, which depend upon an imperfect contact, or a variable resistance, or a supplied source of electricity. Our invention is thus clearly 10 differentiated from coherers, and imperfect contact, or microphonic, wave responsive devices, and also from other wave detectors which necessarily require to be included in a battery circuit for their successful operation. 15 We wish it to be understood that we do not desire to be limited to the exact details of construction shown and described, for various modifications will occur to a person skilled in the art. 20 What we claim as our invention, is:—

1. In the art of wireless telegraphy, a wave responsive device, consisting essentially of a body of zinkite.
2. A member of an oscillation receiver, which consists of the electrical conductor zinkite.
3. A member of an oscillation receiver, which consists of a mass or body of zinkite in crystalline form.
4. In the art of wireless telegraphy, a wave responsive device, consisting essentially of a concrete mass of red oxid of zinc.
5. In the art of wireless telegraphy, a wave responsive device, consisting essentially of a concrete mass of red oxid of zinc in crystalline form.
6. A wave responsive element composed mainly of the red oxid of zinc and small amounts of other elements.
7. In wireless telegraphy, as a wave responsive device, a mass of metal compound comprising a plurality of conducting elements one at least of which is composed essentially of the red oxid of zinc.
8. In wireless telegraphy, a receiver comprising a transforming or converting couple having an element consisting largely of the red oxid of zinc.
9. In wireless telegraphy, a wave responsive device possessing rectifying properties and consisting of an electrically conducting chemical compound comprising the red oxid of zinc.
10. In the art of wireless telegraphy, as a wave responsive device, a mass of wave detecting material, in combination with a divided or bi-faced element.

11. In the art of wireless telegraphy, as a wave responsive device, a mass of wave detecting material, in combination with a 60 divided or bi-faced element, consisting respectively of conducting and insulating portions.

12. In wireless telegraphy, as a wave responsive device, a mass of wave detecting 65 material, in combination with a divided or bi-faced element, and with means for adjusting the contact between the two in a line not coincident with both of the axes of the same. 70

13. In wireless telegraphy, as a wave responsive device, a mass of wave detecting material, a holder therefor, a relatively eccentrically mounted coöperating member projecting laterally from its axis and comprising an electrically conducting element, and means to hold the same so that it may be given a longitudinal as well as a rotative or lateral movement, in combination with means to hold the said member under 80 tension and to adjust it and make a good contact between the wave detecting material and the electrically conducting element in a line not coincident with both of the axes of the same. 85

14. A member of an oscillative receiver which consists of an electrically conducting chemical compound comprising 19.74 parts of oxygen and 80.26 parts of zinc. 90

15. In wireless telegraphy, a wave responsive device possessing rectifying properties and consisting of a mass of oxid of zinc comprising 19.74 parts of oxygen and 80.26 parts of zinc in chemical combination. 95

16. In wireless telegraphy, a wave responsive device possessing rectifying properties and consisting of a mass of oxid of zinc comprising zinc, oxygen, and manganese in chemical combination. 100

17. In wireless telegraphy, a wave responsive device possessing rectifying properties and consisting of a mass of oxid of zinc comprising zinc, oxygen, manganese, and iron in chemical combination. 105

In testimony of the foregoing specification we do hereby sign the same in the city of New York, county and State of New York this 20th day of April 1907.
